ATTORNEY

UNITED STATES PATENT OFFICE.

HENRY J. HEINZ, OF PITTSBURG, PENNSYLVANIA.

DESIGN FOR A BOTTLE.

SPECIFICATION forming part of Design No. 19,911, dated June 17, 1890.

Application filed May 20, 1890. Serial No. 352,541. Term of patent 7 years.

To all whom it may concern:

Be it known that I, HENRY J. HEINZ, a citizen of the United States, residing at Pittsburgh, in the county of Allegheny and State of Pennsylvania, have invented and produced a new and original Design for Bottles, of which the following is a specification, reference being had to the accompanying drawing, forming part thereof, in which the figure 10 is a side view of a bottle showing my design.

The leading feature of the design consists in the representation of the series of flat faces or panels A, extending from the bottom of the bottle to about its middle and having their

side edges vertical and parallel, and the converging edges or sides B B, tapering inward from the upper end of the flat paneled representations. 15

The panel-like representations A are shown with their side edges parallel with each other. 20

What I claim is—

The design for a bottle herein shown and described.

HENRY J. HEINZ.
